United States Patent Office

Des. 212,582
Patented Nov. 5, 1968

212,582

VENTILATED SAFETY HELMET OR SIMILAR ARTICLE

Frederick W. Feldmann and Rodney S. Hill, Dover, Del.,
assignors to ILC Industries, Inc., Dover, Del., a corpora-
tion of Delaware

Filed Feb. 6, 1968, Ser. No. 10,464

Term of patent 14 years

(Cl. D2—231)

FIG. 1 is a side elevational view of a ventilated safety helmet showing my new design;

FIG. 2 is a top plan view thereof;

FIG. 3 is a front elevational view; and

FIG. 4 is a rear elevational view.

We claim:

The ornamental design for a ventilated safety helmet or similar article, as shown.
